TRAFFIC SIGNAL

William J. Leppert, New Orleans, La.

Application October 18, 1944, Serial No. 559,221

8 Claims. (Cl. 177—329)

The present invention relates to improvements in traffic signals.

The present invention deals with the problem of correcting provable flaws in existing methods of devising and constructing the standard street signals used throughout the country and abroad for controlling motor vehicle traffic and adequately advising pedestrians at controlled street intersections.

The several varieties of signal devices used for this purpose on the streets are open to numerous criticisms. They are, without exception, overly heavy; they are extremely fragile; they are made, in many instances of material fashioned as castings of low grade; they involve necessity of high skill for installing and servicing; they are costly beyond need and they involve the use of fragile light bulbs to a number far in excess of actual scientific requirements. This latter fundamental fault stems from a misconception of the fundamental principle of a traffic signal device.

Manufacturers of street signal traffic devices were led into error by wrongfully believing that the light emitted by the signaling device should be projected in a conelike shape after the manner found in lanterns, flashlights, or automobile headlights. In each of these devices one finds that the source of light throws its beams upon one or more parabolic reflectors which cast these beams upon colored lenses in their path. These lenses multiply the intensity of light and, because of the reflector behind the bulb, these rays are thrown out exactly as is done with the headlights on automobiles.

Because these street signal traffic lights must show illumination in as many as four opposed directions, it naturally follows that such street signals must be equipped with four parabolic reflectors, one behind each of the needed bulbs.

That this concept is wrong has been amply proven by laboratory and street tests. All that the oncoming motorist or pedestrian requires is that, within at least 300' of approach, he can be given a vivid and unfailing warning that he is approaching a street intersection under legal control and that he must govern himself accordingly.

Reflectors of the type generally used are made of glass or brass and must be silvered like a mirror or plated with silver or chromium. These materials are costly. Because the average street signal light is composed of three sections—a red, an amber and a green—the common street signal light has twelve openings, three on each

of its four sides. This involves the use of twelve reflectors and twelve light bulbs and multiplies unnecessarily the use of highly expensive electric wiring. It also involves the unnecessarily high cost of unneeded bulbs, their servicing and the element of "burnout costs."

These signal lights also present other features open to honest criticism. In order to achieve results aimed at by the use of reflectors, the bulb is screwed horizontally into the center of the reflector. The reflector itself is held in position against the interior side of the casing by a hinged spider which is secured by a complicated spring. The circumferential edge of the reflector is affixed to the interior wall of the casing with a gasket intended to form a hermetical sealing. The bulb itself, extending vertically from its central base, protrudes through the wall of the casing and clears the outer surface of the casing. On the outer face of the casing is attached the door which holds the lens. This lens is also hermetically sealed by a gasket and the entire door is swung on hinges and rigidly locked. Viewed horizontally this combination of spider plus reflector plus bulb plus lens and plus door represents a spheroid space within which the light bulb, when activated by current, burns and creates intense heat. This unnecessary ovenlike chamber shortens the life of the gaskets, attacks the rubberoid coating over the wiring and greatly shortens the life of the filament within the bulb. These faults result in wholly unnecessary charges and repeated servicing and replacement.

Other objections to the generally accepted street traffic signal are:

(a) The sealing of the heated air within the spheroid creates sootlike deposit upon the circumference of the reflector and the lens;

(b) This deposit shrinks the circular reflection of light and impedes a clear understanding by pedestrian and motorist;

(c) The horizontal placement of the bulb causes the incandescent grid part of the filament to be placed so close to the concavity of the outer lens that there is created a so called "phantom light." This phantom light is confusing to pedestrian and motorist at all times, but is especially confusing whenever the rays of the ascending or descending sun strike upon them.

The present invention aims to correct the faults in the interest of protecting lives of motorists and pedestrians and in presenting to municipalities perfected street traffic signals at an installation and servicing cost less than they

have been paying and at a maintenance cost so greatly reduced as to impel acceptance by them. To effectuate the remedy requires creation of a traffic signal light which is composed of three essential parts:

First part.—The outer casing which is visible to the public.

Second part.—The light channeling unit which constitutes the heart of the invention.

Third part.—The wiring system.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a front elevational view of an improved traffic signal constructed in accordance with the present invention, and with parts broken away and parts shown in section.

Figure 2 is a horizontal section taken on the line 2—2 of Figure 1.

Figure 3 is also a horizontal section taken on the line 3—3 of Figure 1.

Figure 4 is likewise a horizontal section taken on the line 4—4 of Figure 1 with the hoods shown in plan.

Figure 5 is a perspective view of the lamp base adjustable holder.

Figure 6 is a vertical section taken on an enlarged scale on the line 6—6 in Figure 8 and showing the improved channeling unit as mounted in the wall of the casement which is shown in fragmentary section.

Figure 7 is a similar view with the channeling unit shown as detached from the casement wall.

Figure 8 is a front elevational view of the device shown in Figure 6 taken from the left hand side of Figure 6 and with parts broken away and parts shown in section, and

Figure 9 is a front elevation of a fragment of a wall of the casement with the channeling unit detached and removed.

Referring more particularly to the drawings, and for the present to Figures 1 to 4 inclusive, 10 designates generally a casement which may be mounted upon an appropriate base 11 carried upon a hollow or other standard 12, or the casement may be suspended after any acceptable manner from an arm extending horizontally from a structure or a post or standard.

A cable 13 let in through the hollow standard 12 carries the necessary bundles of electric wires which convey current from an external source to the lighting bulbs and timing device in a manner according to conventional practice by which the timing device automatically provides for the electric current to be conveyed successively to the different bulbs in the several compartments.

While the casement may be made of any suitable material and in any suitable form, economically it is manufactured from sheet metal which is originally in a flat sheet at which time twelve holes may be pierced through the sheet metal having a preferable diameter of $8\frac{1}{2}$ inches. These holes 14 are shown more particularly in Figures 7 and 9 and they receive therethrough the various channeling units as hereinafter described. After the holes 14 have been punched in the metal the entire sheet will be placed in a break which will bend it into the form of a box or into rectangular form, as shown in Figures 3 and 4. Such box or casement will probably be approximately thirty-six inches high. The free ends of

the sheet are brought together and welded, as indicated at 15 in Figure 3, or otherwise secured together. The casement 10 thus has four sides, presenting a side wall to each direction of a street intersection; and the casement 10 is sufficiently high to yield three separate light compartments.

At the upper end the casement 10 is closed by a removable cover 16. Such cover 16 may be carried upon the casement and fastened thereto in any appropriate manner. In one form of the invention as shown in Figures 1 and 3, lower opposite side edges of the cover 16 are formed in the inturned flanges 17 adapted to slide upon the outwardly projecting edges 18 of a top plate 19 secured to the casement. When the cover 16 is slid into place a bolt or other fastening 20 (Figure 3) may be passed through the flange 17 and the outwardly projecting edge 18 to hold the parts in assembled relation.

The top plate 19 has an opening 21 through which heat generated in the casement 10 by the lamps may ascend into the cover 16 and be met by a distributing plate 22 (Figures 1 and 2). As shown in Figure 2 such distributing plate may be square or rectangular in plan and rotated angularly with respect to the corner portions of the cover 16 which is pyramidal in shape whereby the corners of the distributing or baffle plate 22 are offset from the corner portions 23 of the cover 16 and the flat sides of the plate 22 are presented to these corner portions 23. The corners of the plate 22 may be held by appropriate clips or fastenings 24 to the walls of the cover 16 between the corner portions 23. Thus the ascending heat directed by the central opening 21 in the top casement plate 19 is directed against the blank wall of the baffle plate 22 and caused to move out horizontally therefrom toward and against the upwardly convergent walls of the cover 16 by which such horizontally diverted heated air ascends along such convergent walls around the edges of the baffle plate 22 and into and through a perforation 25 in the top of the cover 16. Surrounding the perforation 25 is a ventilator having a closed top 26 which overhangs the vertical tubular wall 27. In the wall 27 are apertures 28 in the same horizontal plane with the dependent flange 29 of the closed top 26 it being understood that the flange 29 is spaced outwardly from the perforated wall 27 whereby to deflect the heated air issuing from the apertures 28 downwardly and outwardly beneath the flange 29.

The top plate 19 may be rigidly fastened to the casement 10 to impart rigidity to the upper end of the casement 10. As the plate 19 projects on all four sides of the casement 10, these projections form a shelf for deflecting rain.

At the bottom of the casement 10 is a bottom plate 30 which may be welded or otherwise affixed to the lower edge of the casement sheet and tends to impart rigidity thereto. This bottom plate has one or more slots 31 therethrough for accommodating the several sets of wires 32, 33 and 34 which branch from the cable 13 and are led to serve various compartments of the casement 10. The lowermost compartment 35 is comprised between the bottom wall 30 and a horizontal partition 36 which extends across between the four walls of the casement and is supported by angle irons or may be welded in the casement or otherwise secured in place. A second similar partition 37 is mounted in the casement in spaced relation above the partition 36 so as to comprise

between the partitions 36 and 37 the intermediate or middle compartment 38.

The top compartment 39 is comprised between the upper partition 37 and the top plate 19. If desired a separate floor plate or partition 40 may be mounted in the casement in spaced relation above the bottom plate 30 to form the bottom or floor of the lowermost compartment 35. The partition 35 forms the roof of this lowermost compartment and the floor of the intermediate compartment 38; and in like manner the partition 37 serves both as the roof of the intermediate compartment 38 and the floor of the uppermost compartment 39. Thus three vertically superimposed compartments 35, 38 and 39 are provided in the casement 10 and supported upon the base 12 which base may be ornamental if desired.

In each compartment there is but a single electric light bulb or lamp. These lamps are designated at 41, 42 and 43. From Figures 1 and 4 it will be seen that the lamps are supported with their socket axes vertically. Each lamp is mounted upon an adjustable holder, one form of which is illustrated in Figure 5. One such holder is mounted upon the floor of each compartment.

Referring more particularly to Figure 5 a lamp socket 44 is shown as disposed with its axis vertically and with its base resting upon and affixed to a cradle plate 45 having upstanding slotted side walls 46, the slots of which are indicated at 47. The side walls 46 slide up and down with the cradle plate 45 between vertical carrier plates or walls 48 which are suitably erected and affixed upon the floors of the compartments. The flanges or feet 49 may be suitable for this purpose and to provide ample surfaces for welding, brazing or otherwise affixing the carrier plates to the compartment bottoms, both of which members may be advantageously of metal. Bolts 50 pass horizontally through the carrier plates 48 and through the slots 47 of the side walls 46. The heads 51 of the bolts and the winged or other nuts 52 may be wider than the widths of the slots 47. By loosening the nuts 52 the cradle plate 45 carrying the lamp socket 44 and the lamp therein may be moved up or down; and after adjustment the nuts 52 may be retightened to preserve that adjustment.

It is important to observe that in accordance with this construction the light bulbs are screwed vertically (and not horizontally) into the adjustable sockets 44, the height of which may be manually adjusted. Thus the illuminated grid section or filament in the bulb can be exactly leveled with the center of each of the four lenses of the channeling units as hereinafter described and as shown by the circled background in Figure 1.

The twin wires 33 from the cable 13 lead upwardly through the slot 31 of the bottom plate 30 and a central opening of the bottom partition 40 and are connected with the socket 44 in the lowermost compartment 35.

The twin wires 34 are directed to the left and pass upwardly through corner portions of the partitions 40 and 39 as shown in Figures 1 and 4 and emerge in the central compartment 38 where they are connected to the socket in that compartment. While the wires 34 pass through vertically aligned openings in the partitions 40 and 39, such wires are led through elbows 53 and 54 to avoid the light from one compartment spreading to another compartment.

The twin wires 32 branch to the right in Fig-

ure 1 and ascend through elbows 55 arranged at the opposite corner portions of the partitions 40, 36 and 37 to bring the wires or leads 32 into the uppermost compartment 39 where the same are connected with the light bulb socket in that compartment.

The partitions 40, 36 and 37 may be square pieces of metal rigidly affixed to each of the four sides of the casement box and are preferably solid except where pierced for wiring and ventilation purposes.

Each compartment has a single lamp but four light channeling units as shown in Figure 4. With three compartments there are twelve such channeling units in all.

One such channeling unit and its method of mounting are shown in Figures 6 to 9 inclusive. In Figure 9 a fragmentary portion of the casement is shown in which one hole or opening 14 appears. About this opening 14 is a ring 56 which is spaced radially outwardly of the opening 14 and which outstands from the outer face of the casement wall 10 as more clearly appears in Figure 7. This ring may be of metal, welded or otherwise secured to the casement wall 10. Also carried by the casement wall at the top of the ring 56 is a lug 57. Also carried by the casement are detents or finger latches 58 pivoted upon the pivots 59 and having the offset free ends 60. As shown in Figures 8 and 9 these finger latches or pivot detents 58 are three in number with one at the bottom of the circle of the ring 56 and two at the upper side portions of said ring.

Referring more particularly to Figures 6 and 7, the light channeling unit comprises a frustoconical casing 61 to the smaller end of which is attached a tubular lens holder 62 having a diagonal flange 63 which externally laps the smaller end of the casing 61 and may be welded or otherwise affixed thereto. A vertical inturned flange 64 on the small end of the cone casing 61 constitutes an abutment for the edge of a small convex colored lens 65. The rim of this lens 65 slides freely in the tubular lens holder 63. A disc diffusion lens 66, preferably of white flash glass, is also slidably mounted in the tubular lens holder 62 and moved up against the circular rim of the small convex colored lens 65. A retainer ring 67 of spring wire serves to retain the diffusion lens 66 in place and incidentally to also hold in place the small convex colored lens 65. The retainer ring 67 is mounted in a swivel keeper 68 carried within the tubular lens holder 62 to enable the retainer ring 67 to be swung out to the position indicated in Figure 6 to admit the lenses and to permit of the removal of the same.

The lower spaced ends 69 of the split retainer ring 67 are outturned downwardly into parallelism and are in juxtaposition, as indicated in Figure 8, for convenience in being simultaneously grasped by the hand of the operator and squeezed together whereby to free such ends 69 from undercut notches 71 in the lower part of the tubular lens holder 62 into which such outturned ends 69 are automatically moved by the inherent resiliency of the spring retainer ring 67 in attempting to expand radially outward. A slot 70 communicates with the undercut notches 71 and opens through the inner edge of the tubular lens holder 62 to permit such outturned ends 69 when squeezed together to swing on the swivel keeper 68 out of the slot 70 and to the position indicated in Figure 6.

A hood 72 of a conventional form is carried at the larger end of the cone casing 61. The hood

72 is carried by a ring 79 which may be integral with the metal stock of the hood. This ring 79 has an outturned flange 73 which abuts against an outturned flange 74 of the large end of the frusto-conical casing 61. It will be noted from Figures 6 and 7 that the flange 74 is deeper in a radial sense as compared with the flange 73 which produces a shoulder or abutment against which the ring edge of the large convex colored lens 75 engages, such lens being slidable from the outer side into the hood ring 79 in which it is retained at the outer side by a retainer ring 76 of spring wire carried by a swivel keeper 77 mounted at the upper portion of the hood ring 79. The outturned free spaced ends 78 of the retainer ring 76 cooperate with a slot 80 and undercut notches 81 in the hood ring 79 similar to the parts 70 and 71 previously described. The swing out position of the spring retaining ring 76 is shown in Figure 6.

An attaching ring 82 is affixed externally to the hood ring 79 and preferably to the flange 73 thereof. The flanges 73 and 74 and the attaching ring 82 may all be of metal and welded together or affixed in any other suitable manner. The attaching ring outstands beyond the outer edges of the flanges 73 and 74 and carries a right angularly turned flange 83 substantially concentric with and spaced radially outwardly from the flanges 73, 74. The attaching ring 82, its flange 83 and the combined flanges 73, 74 constitutes an annular groove for rather snugly receiving the casement ring 56; or more properly speaking for fitting upon three sides of the ring 56, the inner side of the ring being against the casement wall.

As shown in Figure 6, the flange 83 lies outwardly of the ring 56 with the flanges 73, 74 lying radially inward of the same and with the inner flange 74 lying against that area of the casement wall that is included within the ring 56. The attaching ring 82 lies against the outer face of the ring 56. Thus the casement ring 56 and the attaching ring 82 and its associated parts including the flange 83, 73 and 74 form a mechanical couple for interfitting to center and orient the channeling unit upon the casement in correct positional relationship to the casement opening or hole 14. The flange 83 is made at its top portion with a notch 84 constructed to rather snugly fit about the casement lug 57. This is for the purpose of rotationally or angularly orienting the channeling unit with reference to the casement opening and with respect to the vertical and to the horizontal in order that the hood 72 and the cross ribs of the lenses 65 and 75 may assume a correct and true position.

Figure 7 shows the channeling unit apart from the casement 10, while Figure 6 shows the unit in place in the casing and with the finger latches 58 rotated to locking position with the outwardly offset free end portions 60 thereof engaging the outer face of the attaching ring 82.

One of the important factors of the light channeling unit is that the arrangement of lenses avoids confusion so frequently resulting from the breakage, through accident in handling or by vandalism, of the conventional outer lens found in the usual type traffic signal light. When this outer lens is broken in those lights, the bulb, unless it too is broken, shows merely as a white light. It is obvious that the motorist or pedestrian is without a warning advice to govern himself. In the improved channeling unit, even though an outer red or green or amber lens is

broken, an inner lens of the same color would remain unbroken. In other words the people governed by the light are doubly protected by the channeling unit than under the conventional type of traffic light now in use.

In the intermediate compartment 38 of the casing all four of the light channeling units will have amber colored lenses. In other words both inner and outer convex lenses 65 and 75 of the four units will all be of amber colored glass.

In the top and bottom compartments of the casing both lenses of each channeling unit will be red or green, it being understood that two diametrically opposite channeling units in each compartment will have green colored small and large convex lenses and the other two diametrically opposite units will have both convex lenses red in color; with the red lenses alternating with the green in said top and bottom compartments so that when the lamp 43 in the top compartment is illuminated and both other lamps 41 and 42 dark, green lights will be seen at opposite sides of the signal in one direction and red lights at opposite sides of the casement in an intersecting direction. When the lamp 41 is illuminated, and the other two lamps 42 and 43 dark, the lower compartment will show two green lights in the directions in which the red lights of the top compartment appeared and two red lights in the directions in which the green of top compartment appeared. The timing device in accordance with conventional practice will energize the lamp 42 of the intermediate compartment 38 between each change of signals and when such lamp 42 is energized it will show an amber color in all directions.

To a marked degree the casement 10 covers the element of stability and structure. Rigidity of the entire reinforced three compartments lies in the fact that the casement is a solid piece and not composed of separable elements.

There are no doors whatever in the casement. This construction eliminates the twelve doors customarily used. The ease with which the light channeling unit—a complete assembly—may be removed from the face of the casement structure eliminates all need of doors, all hinges and locks.

When the single lamp is illuminated in a compartment its rays strike the disc lens 66 of white flash glass which diffuses the light to all parts of the concave side of the smaller colored lens 65. This colored lens 65 is a spread light lens and it spreads the light rays to all parts of the interior of the concave side of the outer convex colored lens 75 which thus presents to the eye of the motorist at a suitable distance from the signal an area of colored light suitable for conveying the necessary warning signal.

There are no reflectors in the unit. The light, diffused by the lamps, sifts through the white flash glass 66, strikes the inner spread light lens 65, and is channelled, without reflectors, to the circular outer lens 75.

Placement of the smaller lens 65, as is done in the channeling unit, coupled with the use of the white flash glass 66, kills the phantom light (against which complaint is general) by a diffusing instead of emphasizing the incandescence of the filament at the grid.

No attempt is made to exclude air, no gaskets are used and, because of lower temperature, there will be no smudging due to excessive heat created within a spheroid vacuum.

The casement is a solidly built single unit and not an assembly. It involves rigid construction

due to its rectangular assembly and to its arrangement of partitions and to its top and base units. Moreover the casement provides ample and constant ventilation in which the air ascends through the open base 12, slot 31 and through the elbows through which the wires pass. The heat produced by the three bulbs will create convection currents drawing cold air up through the base and requiring the egress of the warm air out of the ventilator 26 at the top which will protect 10 the interior of the casement from the elements.

The interior wiring is so staggered at opposite corners, as to assist, instead of confusing, repair men in tracing the wiring. The vertical placement of the light sockets, as against the horizontal placement, minimizes damage from road 15 vibration and protects both wiring and filaments.

The adjustable socket table at the bottom of each compartment permits actual, easy and quick focusing of grid regardless of size of light bulb 20 used.

The casement may be fitted with conventional tops and bottoms. The particular construction of the casement and the particular construction of the base and the top cover are all desirable and preferable constructions but they may be varied without departing from the spirit of the 25 invention.

The casements have no movable parts, except the finger latches 58 and the adjustable light 30 socket bases.

The snugness of fit and means of fastening the light channeling units to the casement by the three fingers 58 eliminate the necessity for doors or hinges.

The channeling units can be slipped into position by the use of the fingers alone. They require no tools for servicing.

The main feature of the invention is the construction in a traffic signal of an arrangement of compartments that without doors, hinges, locks and gaskets and with only three light sources is enabled without the use of reflector and by employment of the improved channeling unit to give dependable traffic signal warnings at extremely low cost and at a minimum need for servicing.

It is obvious that various changes and modifications may be made in the details of construction and design of the above specifically described embodiment of this invention without departing from the spirit thereof, such changes and modifications being restricted only by the scope of the following claims:

What is claimed is:

1. An improved traffic signal comprising hollow base, a casement supported upon said base, a plurality of horizontal partitions dividing said casement into vertically superposed light-tight compartments, lenses in said several compartments, an electric lamp in each compartment, a cable comprising a plurality of pairs of circuit wires entering through the hollow base, one pair of wires extending independently of the other wires to the lamp in the lowermost compartment, a second set of wires extending up through corner portions of the lowest and next lowest partitions and to the lamp in the second lowest compartment, a third set of wires led independently through opposite corner portions of the lowermost and the next two higher partitions and to the lamp of the third lowest compartment, elbows in the corner portions of the partitions through which said wires are passed without permitting transfer of light from one compartment to another, said elbows being of sufficient diameter to 75

accommodate said wires and to provide ventilating ducts for the passage of convection currents of air upwardly from the hollow base as induced by the heat of the lamps, and a cover for the casement having a weather protected ventilator thereon, allowing the egress of heated air from the casement.

2. In a traffic signal as claimed in claim 1, a baffle plate in said cover of substantially rectangular form secured by its corner portions to upwardly convergent walls of the cover between corner portions of a pyramidal cover.

3. An improved traffic signal comprising a casement having a compartment therein with an opening therein, a light source in said compartment, and a channeling unit comprising a housing having lens seats therein, small and large colored lenses mounted in said lens seats, and a diffusion lens mounted in said housing inwardly of the small colored lens, and means to secure said housing removably to the casement.

4. A light channeling unit for use with traffic signals comprising a frusto conical casing, a tubular lens holder carried thereby and having an abutment therein, a small colored spread light lens in said holder fitted against said abutment, a diffusion lens fitted in said holder within the first named lens, means in said holder for removably retaining both lenses in place, a hood connected to the other end of said frusto conical casing and forming a seat therewith, a large colored lens fitted against said seat, means in said hood for removably retaining said large lens in place against said seat, abutting flanges between 35 said casing and hood, and a ring carried by said hood adjacent said abutting flanges, said ring having a flange in its outer edge concentric with said abutting flanges, said ring flange having a notch therein.

5. An improved traffic signal comprising a casement having a compartment therein, a lamp in the compartment, a lens holder in said compartment, a lens removably mounted in the holder, a resiliently expandable ring pivotally mounted in said holder for engaging said lens and having free outturned spaced ends, said holder having a slotted wall portion with uncut notches adjoining the slot, said slot positioned and arranged to permit the passage of the ends when squeezed together, said ends adapted to expand into said undercut notches when the ends are released.

6. An improved traffic signal comprising a casement, a support for said casement, a plurality of vertically spaced partitions dividing said casement into a number of vertically superposed light-tight compartments, lenses in said several compartments all communicating with the same common interior space of the compartment and facing in different directions, a single electric lamp in each compartment accessible to all the lenses of the respective compartments, electric wires brought upwardly through said casement and through said partitions to the several electric lamps, elbows in the partitions through which said wires are passed without permitting transfer of light from one compartment to another, said elbows being of sufficient diameter to accommodate said wires and to provide ventilating ducts for the passage of convection current of air upwardly through the casement as induced by the heat of the lamps, and a cover for the casement having a ventilator thereon allowing the egress of heated air from the casement.

7. An improved traffic signal comprising a case-

ment having a compartment with an opening therein, a lamp in said compartment, a light channeling unit, and means for securing said light channeling unit in place comprising a ring outstanding from the casement, a complementary 5 ring on the unit having a groove for snugly receiving said casing ring, and removable means for holding the unit ring upon said casing ring.

8. An improved traffic signal comprising a casement having a compartment with an opening 10 therein, a lamp in said compartment, a ring affixed to the casement outside said compartment

and radially spaced from the opening, a lug projecting off said ring, a light-channeling unit adapted to be removably let in through the opening, an attaching ring on said channeling unit having a groove to encompass said casement ring on the three exposed sides thereof, said attaching ring also having a notch to receive said lug to orient the unit angularly, and latch means on the casement adapted to engage said attaching ring.

WILLIAM J. LEPPERT.
